UNITED STATES PATENT OFFICE

NAASON Z. BUTTERICK, OF MIAMI, FLORIDA

WARDROBE SUITCASE

Application filed January 12, 1928. Serial No. 246,236.

This invention relates to suit cases, and more particularly to that type of suit case especially designed to carry clothing or garments without danger of wrinkling.

5 The main purpose of the present invention is to provide a suit case of the so-called "wardrobe" type having means to secure the opposite ends of garments or clothing in such a manner that upon closing the suit case 10 the garments are automatically straightened out.

A further object of the present invention is to provide means for preventing any displacement or wrinkling of the garments in 15 the event of the upsetting or overturning of the suit case.

Suit cases of this general class have been manufactured heretofore in which there has been provided a structure, comprising a plurality of hangers, upon which the garments are adapted to be hung, thereby supporting the upper portion of such garments, but no means has been provided for supporting the lower portions of the garments. According 25 to my invention, garments placed in such suit cases will collapse toward the center of the suit case when the case is closed. Generally a sufficient number of garments are placed in the case to fill it, causing the garments to crowd 30 each other and become wrinkled. With the present invention the garments are supported not only at both ends but also adjacent the center, thereby entirely eliminating any possibility of wrinkling or displacement regardless of whether only a single garment or 35 the full capacity of the suit case is carried.

A further object of my invention is to provide a suit case which will operate automatically upon the closing of the case to pull 40 the ends of the garments in opposite directions from the center, thereby maintaining the garments in a slightly taut straightened position.

In the accompanying drawings illustrating one embodiment of my invention—

Figure 1 is a plan view of the entire suit case showing the same in open position.

Figure 2 is a longitudinal sectional view through the case also showing it in open position.

Figure 3 is a longitudinal sectional view through one of the side portions of the case and the central portion thereof, the latter being illustrated in dotted lines in open position.

55 Figure 4 is a fragmentary detail sectional view taken on the line 4—4 of Figure 2.

Figure 5 is an end elevation of the entire suit case, illustrating the same in closed position.

60 Figure 6 is a longitudinal sectional view through the suit case showing a plurality of garments positioned therein.

Figure 7 is a detail view of one of the garment hanger members detached.

65 Figure 8 is a detail view of one of the members for the support of the lower extremity of the garment.

Figure 9 is a side elevation of Figure 8 illustrating the same in open position.

70 The suit case comprises a pair of side sections 1 hinged at 1^a to a central bottom section 2, which is substantially U-shaped and is preferably slightly less in width than the side sections, so that when the case is closed the portions of the side sections adjacent the hinges 1^a will overlie the upstanding walls 2^a of the bottom section thereby providing a substantial structure. The side sections are provided with a pair of handles 1^b for the 75 convenient carrying of the case, and may be further provided with the usual locks or clasps.

75 Each side section includes upstanding side walls 1^c and an end wall 1^d. Brackets or 80 guide members 3 are rigidly secured to the side walls by means of screws, rivets or the like; the said guide members being preferably arcuate in shape and being disposed in opposed relationship adjacent the end wall of 85 the side sections. Each bracket is provided with an arcuate guiding slot or track 3^a adapted to receive a pin 4^a of a hanger supporting member 4 which is pivotally secured at 4^b to the side wall of the side section.

90 Garment hangers 5 are provided comprising a garment receiving portion 5^a and a suspending portion 5^b. The portion 5^b is substantially bar-like and is provided at its extremities with pins 5^c, one of such pins being 95 100

resiliently mounted and comprising a plunger provided with a knob or handle 5^a for the convenient manipulation thereof (see Figure 7).

5 Each hanger supporting member 4 is provided with a plurality of spaced apertures 4^c adapted to receive the pins 5^b upon the garment hangers. I have shown a plurality of garments disposed upon hangers properly 10 mounted within the suit case. One of the side sections is utilized for the mounting of the hangers and upper portions of the garments, the other side section receiving the lower portions of such garments.

15 I provide retaining members 6 to receive the lower extremities of the garments, each member 6 comprising a pair of spaced bars 6^a and a flexible strap 6^b of webbing, canvas or any other suitable material disposed therein- 20 between and in a plane slightly above that of the bars. The strap 6^b is secured at one end and provided at the other end with a fastening member 6^d as a buckle, clasp or the like. The members 6 are provided at each 25 extremity with a pin 6^e, similar to the pins 5^e, one of the said pins comprising a resilient plunger having a knob or handle 6^e, to permit insertion or withdrawal. The bars 6^a, may, if desired, be covered on their upper 30 surfaces, as by a rubber or cloth facing for the protection of the garments adapted to be supported thereby. It will be readily under- 35 stood from the above description of the mounting of the garment hangers 5, that the members 6 in like manner may be as conveniently mounted between similar opposed sup- 40 porting members 4^a.

To support and retain the central portions of the garments, I provide a rod or bar 7 45 adapted to be mounted within apertures 8^a disposed in guide brackets 8 rigidly secured to the walls 2^a of the bottom section of the suit case.

In packing the suit case, the case is first 50 opened to the position illustrated in Figures 1 and 2 of the drawings. A garment is then placed upon one of the hangers 5, and the hanger is then mounted in the lowermost holes of the pair of supporting members 4, 55 the garment then being disposed or adapted to lie flat within the case. One of the members 6 is then secured to the lower end of the garment, the bars 6^a being adapted to lie beneath the garment while the strap 6^b is fastened thereabove, thus slightly binding the 60 garment in position between the said strap and bars. The member 6 is then mounted in the lowermost holes of the pair of supporting members 4^a. In like manner any desired 65 number of garments are positioned therein, after which the bar 7 is mounted within the apertures in the brackets 8 so as to lie immediately above the uppermost garment. The garments are thus securely supported at the

Links 9 upon opposite sides of the case are secured at 9^a to the hanger supporting members 4, and 4^a, the opposite ends of the links being pivoted to the side walls 2^a of the bottom sections.

Upon opening the suit case, the outer ends 70 of the supporting members 4 will be guided, by the pins 4^a within the slots or tracks 3^a and will be moved by the links 9, toward the center of the case, to the position shown in Figure 2 of the drawings. In like manner upon closing the case, the supporting members will be automatically moved to the position illustrated in Figures 3 and 6 of the drawings.

When the suit case is open the supporting members 4 will be inclined inwardly ready 75 for the packing of garments therein. Upon closing the case, the supporting members 4 are automatically swung by the pivotal link 80 connection 9, from the inwardly inclined position shown in Figure 2, to an outwardly inclined position shown in Fig. 6, thereby pulling 85 the upper and lower portions of the garments in opposite directions away from the 90 center. The garments are thereby straightened and held slightly taut, free from wrinkles and free from any possibility of displacement or wrinkling. From an examination of 95 Figure 6 of the drawings it will be seen that the angular relationship of the members 4 is such as to position adjacent garments in slightly offset or staggered relationship, thus preventing any crowding or binding of the 100 upper portions of the garments which are generally heavier or thicker.

I claim:

1. In a sectional suit case of the class set forth, in combination, garment retaining members in both sections, each adapted to support an extremity of a garment, means for supporting the center of the garment, and means automatically operable upon closure of the suit case to move such retaining members in opposite directions from the center of the garment.

2. In a sectional suit case of the class set forth, in combination, garment retaining members in both sections, each adapted to support an extremity of a garment, means for supporting the center of the garment, and means automatically operable upon closure of the case to move the retaining members in opposite directions from said central support, and to dispose the garments in offset relationship and in a straightened and taut condition.

3. A suit case of the class set forth comprising side members and a bottom member, means for supporting a plurality of garments therein, said means comprising retaining members pivotally secured to the side members and adapted to receive the extremities of garment supporting members, adjustable means for supporting the center 125 130

of the garments, and means automatically operable upon closure of the suit case to shift the retaining members on their pivots in opposite directions from said central support, and to dispose such garments in offset relationship and in a straightened and taut condition.

4. A suit case comprising side members and a bottom member hingedly connected, 10 arcuate guide brackets secured to said side brackets, carrier arms pivotally secured to the side members and guided in said brackets, garment retaining members secured to said corner arms, links pivoted at one end 15 to the bottom member and at the opposite end to said arms, and a central supporting member adjustably secured at opposite ends to the bottom member, whereby upon swinging the side members toward each other in 20 closing the case, the retaining members are swung on their pivots in opposite directions thereby stretching the garments supported in said retaining members in opposite directions from said central member and disposing 25 them in offset relationship.

5. In a sectional suit case of the class set forth, in combination, garment retaining members in opposite sections, each adapted to support an extremity of a garment, means 30 for supporting the center of the garment, and means automatically operable upon closure of the case to move the retaining members in opposite directions from said central support, and causing the central retaining members to move the greater distance and the outer members the least distance.

6. In a sectional suit case of the class set forth, in combination, garment retaining members in opposite sections adapted respectively to support the opposite extremities of a garment, means for supporting the center of the garment, and means automatically operable upon closure of the case to 45 move the retaining members in opposite directions from said central support, the central retaining members moving the greater distance, each of the other members moving a lesser distance, the outermost members 50 moving the least distance.

7. In a sectional suit case of the class set forth, in combination, garment retaining members in opposite sections adapted respectively to support the opposite extremities of a garment, means for supporting the center of the garment, and means automatically operable upon closure of the case to move the retaining members in opposite directions from said central support, and causing 55 the inner retaining members to move the greater distance, each of the other members a lesser distance, the outer member the least distance; the members automatically separating from adjacent members during 60 this upward movement, thereby allowing the

various garments to pass one another without interference.

In testimony whereof I affix my signature.

NAASON Z. BUTTERICK.
